United States Patent Office.

THOMAS HOPPER AND HATFIELD HOPPER, OF NEWARK, NEW JERSEY.

Letters Patent No. 69,487, dated October 1, 1867.

IMPROVEMENT IN STEAM CAR-BRAKES.

The Schedule referred to in these Letters Patent and making part of the same.

TO ALL WHOM IT MAY CONCERN:

Be it known that we, THOMAS HOPPER and HATFIELD HOPPER, of the city of Newark, in the county of Essex, and State of New Jersey, have invented certain Improvements in Brakes for Railroad Cars; and we do hereby declare the following to be a full and exact description of the same, reference being had herein to the drawings that accompany this specification and make part of the same.

The improvement consists in the manner of making a continuous connected brake through a whole train of cars; which the engineer can operate instantly as quick as he could blow his whistle for two cars to have their brakes applied, as in ordinary trains, there being only a fireman and one brakeman allowed to one train of cars. The drawing represents two cars with the brakes and their connections.

A is a sliding rod with a flat head, each car having one at either end. A chain, B, passing over sheave-pulleys C¹ and C², is fast to the tail or inner end of the rods A, so that pushing the one in necessarily pulls the other out. These chains are so adjusted that the flat heads on the rods A of two cars shall press together. There being room between the cars and springs attached to the ordinary bumpers, of course there is a continuous varying or changing of the distance, and in consequence thereof the chains will be tightening or loosening as the cars approach or recede from each other. Provision is made to take up what is technically termed "lost motion," by the addition of sliding rods D, which are connected by link and pins E, and are placed under the bumpers F, to be connected by their pins at the same time as the bumpers are connected. Upon the rods the sheave-pulleys C¹ are made adjustable, being held in position on the rods D by the set-screws a. As these rods D move with every motion of the cars, they carry the pulleys with them, and preserve the necessary tightness of the chains to insure a continuous pressure on the flat heads of the rods A. At each end of the car a lever is suspended, with its support on the bar that has on its ends the brake-blocks b. To the upper end of the levers F a chain or rope of wire or fibrous material is made fast, connecting the two levers on each car. The middle of this chain or rope G is secured to the middle of the chain B, between the two sheave-pulleys C¹, and a rod, e, connects the two levers F at their lower ends, so as that when the top end of one of the levers is forced in, by operating the rods A, the top end of the other lever is pressed back against the frame of the car, and the two lower ends are drawn together by the rod e, bringing the brake-blocks b on each end tight to the wheels. It is intended that a small steam-cylinder be placed under the foot-board of the engineer of the train, opposite that flat head of the rod A that will be under the tender, so that an instantaneous direct pressure can be put upon all the brakes at once. It will be seen that instead of a pull upon the main rods A to operate the brakes, we give thereto a receding movement.

We do not broadly claim sheave-pulleys, rods, or chains, but what we do claim, and desire to secure by Letters Patent, is—

1. The combination of the sliding rods A and D with the pulleys C¹ and C², chains B and rope G, when arranged to operate the brake-levers F in the manner and for the purpose herein described.
2. The sliding rods D and adjustable pulleys C¹, when constructed and arranged in the manner and for the purpose herein set forth.

THOMAS HOPPER,
HATFIELD HOPPER.
